UNITED STATES PATENT OFFICE

CARLON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS FOR CONVERTING PETROLEUM OIL

Application filed February 8, 1922. Serial No. 534,858.

This invention relates to improvements in a process for converting petroleum oil and refers more particularly to a process in which the lighter fractions are first distilled from the oil and the oil charge subsequent to this initial distillation, is combined with the reflux condensate and treated in a separate coil wherein the major conversion takes place.

The single figure is a diagrammatic side 10 elevational view of the apparatus. The process is carried on in the following manner.

The oil to be treated is introduced from storage through a line 1 controlled by a valve 2 and is charged by means of a pump 3 through the line 4 in which is interposed a valve 5 to the heating tubes 6 mounted in the lower division 7 of the double-deck furnace 8. Gas burners 9 serve to heat this lower division or compartment. The oil circulated 20 through this initial stage is raised to a temperature above that which will produce distillation of the lower boiling point oil fractions. From the heating coils 6 the heated oil is directed to an expansion or vaporizing 25 chamber 10 where the lighter vapors are relieved from the oil body passing off through a pipe 11 to a water condenser 12. In addition to the lighter fractions which are relieved in this stage, there will also be distilled 30 from the oil any water which is contained therein. Thus, when the oil is drawn from the primary distilling chamber 10 it is in a dry condition as far as water or moisture in the oil is concerned. A pressure gauge 13 is mounted on the distilling chamber 10. The condensed water and lighter oil fractions may be drawn off from the condenser coil through the valve 14. The oil withdrawn from the distilling chamber passes out 40 through the line 15 regulated by a valve 16 and is directed through the upturned vertical portion of this line by means of a suitable pump and introduced into the top of dephlegmator 17 where it serves as a refluxing 45 medium to the oil vapors which rise through this dephlegmating column. After percolating down through the dephlegmator it is collected with what condensate may be separated 50 from the oil vapors in the lower leg 18 of the column and is drawn off therefrom

through a line 19 regulated by a valve 20. Through this line, the raw oil and reflux condensate is passed to the heating coils 21 mounted in the upper compartment 22 of the furnace 8. This compartment besides receiving heat through the checker-work brick partition wall 23 from the lower compartment or division of the furnace, is further heated by burners 24 to a temperature sufficient to raise the oil to a cracking temperature.

The heated oil is passed from the tubes 21 through the transfer line 25 in which is interposed a valve 26, to the expansion chamber 27. The vapors evolved therein produced in the conversion of the oil body, pass off through the vapor line 28 regulated by a valve 29, to the dephlegmator 17, while the unvaporized oil may be maintained at a proper level by withdrawing it intermittently or continuously through the valve 30.

As explained the vapors are dephlegmated by being passed in intimate contact with the oil introduced from chamber 10 which percolates down over the perforated pans 31 arranged in the dephlegmator. The dephlegmated vapors pass off through the pipe 32 to a water condenser 33 and flow down through the pipe 34 in which is interposed a valve 35, to the receiving tank 36 which is equipped with liquid level gauge 37, pressure gauge 38 and a pressure relief pipe 39. A draw-off valve 40 in the bottom of the tank serves to withdraw the distillate from the receiving tank.

By treating the oil in this manner, the lighter distillates may be separately drawn off and collected and the oil relieved of its moisture content prior to its being submitted to the cracking or conversion reaction. In addition to this advantage, the reflux condensate which requires a greater degree of heat than is necessary to distill off these lighter fractions is treated in a separate coil and may be raised to a higher temperature without producing undue conversion in the raw oil charge. It has been found where reflux condensate is combined with and re-treated with the raw oil, that the temperature necessary to produce further conversion of

the reflux is excessive as regards the raw oil and as a consequence accelerates the vaporization to an objectionable degree which produces the formation and accumulation of 5 carbon in some of the heating tubes. Where it is possible to relieve the raw oil of these relatively low boiling point fractions prior to its major conversion, a greater part of this carbon separation may be obviated. By 10 treating gas oil of approximately 32 to 33° Baumé in this manner, a yield of 40% to 50% pressure distillate, having a gravity of from 48 to 51° may be produced.

The operation of the process is preferably 15 continuous and the pressure regulated by the valves may range from 50 to 250 pounds according to the character of the oil treated.

I claim as my invention:

1. A process of oil conversion, consisting in 20 initially passing a stream of charging oil through that portion of a furnace maintained at the lowest temperature, to heat such oil sufficiently to cause vaporization of the lighter constituents and any water contained 25 in the oil, in collecting the heated liquid oil in a body, from which body the vaporized light constituents and water are removed, to be isolated from the process, in simultaneously passing a second stream of oil through that 30 portion of the furnace maintained at the highest temperature, wherein said second stream of oil is raised to a conversion temperature, in passing vapors evolved from oil heated in said second stream to a dephlegmator, in 35 introducing heated liquid oil from said body to said dephlegmator, to act as a dephlegmating medium for the vapors therein, in taking off dephlegmated vapors from said dephlegmator for condensation and collection 40 and in withdrawing unvaporized charging oil and reflux condensate from said dephlegmator, to form the charging oil for said second stream, and in maintaining a superatmospheric pressure on the oil undergoing 45 conversion.

2. A process of oil conversion, consisting in simultaneously passing separate streams of oil through a furnace, one of said streams of oil being passed through that portion of the 50 furnace maintained at the lowest temperature, while the other stream is passed through that portion of the furnace maintained at the highest temperature, in delivering the oil which has been subjected to the lowest temperature 55 to an enlarged chamber, from which vaporous constituents are withdrawn, to be isolated from the process, in passing vapors evolved from the oil which has been subjected to the highest temperature to a dephlegmator, 60 in introducing liquid oil from said enlarged chamber to said dephlegmator, to act as a dephlegmating medium for the vapors therein, in taking off dephlegmated vapors from said dephlegmator, in withdrawing unvaporized liquid oil and reflux condensate from 65

said dephlegmator, to supply the stream of oil which is passed through the portion of the furnace subjected to the highest temperature, and in maintaining a superatmospheric pressure on the oil undergoing conversion in 70 the process.

3. A process for treating hydrocarbon oils, consisting in passing a stream of charging oil through that portion of a furnace maintained at the lowest temperature, in simultaneously 75 passing a second stream of oil through that portion of the furnace maintained at the highest temperature, wherein said second stream of oil is raised to a cracking heat, in delivering the first stream of oil to a zone, from which those constituents vaporizable at the temperature to which such stream of oil has been raised are removed, to be isolated from the process, in delivering the heated oil from said second stream to a second enlarged 80 zone, wherein conversion occurs, in passing vapors from said second enlarged zone to a dephlegmator, in supplying liquid oil from said first zone to said dephlegmator, to act as a dephlegmating medium for the vapors 85 therein, in withdrawing unvaporized liquid oil and reflux condensate from said dephlegmator, to supply the charging oil for said second stream, and in maintaining a superatmospheric pressure on the oil undergoing 90 conversion in the process.

4. A process for treating hydrocarbon oil comprising passing a stream of charging oil through a portion of a furnace wherein said oil is heated to a temperature sufficient to 100 volatilize the lighter constituents and water content in the charging oil, simultaneously passing a second stream of oil through another portion of the furnace wherein said second stream of oil is raised to a cracking 105 temperature, delivering the first stream of oil to a zone from which those constituents vaporizable at the temperature to which said stream of oil has been raised are removed to be isolated from the process, delivering the 110 heated oil from said second stream to an independent enlarged zone wherein conversion occurs, passing vapors from said independent enlarged zone to a dephlegmator, supplying liquid oil from said first zone to said dephlegmator to act as a dephlegmating medium for vapors therein, withdrawing unvaporized liquid oil and condensate from said dephlegmator to supply the charging oil for said second stream, and maintaining a superatmospheric pressure on the oil undergoing 115 conversion in the process.
